UNITED STATES PATENT OFFICE.

MAX BARSCHALL, OF NEW YORK, N. Y., ASSIGNOR TO THE FIRM AUSFUEHR-
UNGEN FUER EISENBAHN OBERBAU, ABTH. STOSSFANGSCHIENE, SIEGM.
EPPENSTEIN, OF BERLIN, GERMANY.

RAIL-JOINT.

SPECIFICATION forming part of Letters Patent No. 708,009, dated September 2, 1902.

Application filed January 6, 1902, Serial No. 88,518. (No model.)

To all whom it may concern:

Be it known that I, MAX BARSCHALL, a subject of the King of Saxony, residing at the city of New York, borough of Manhattan, county and State of New York, have invented 5 certain new and useful Improvements in Rail-Joints, of which the following is a specification.

My invention relates to rail-joints, and has 10 for its object to provide a safety-rail or auxiliary support at the joint of the main rails and to so construct the auxiliary rail that it will be exceedingly strong and readily manufactured by rolling.

15 My invention will be fully described hereinafter and the features of novelty pointed out in the appended claims.

Reference is to be had to the accompanying drawings, in which—

20 Figure 1 is a cross-section of one form of my improved rail-joint. Fig. 2 is a similar view of another form of my invention. Fig. 3 is a plan thereof, and Fig. 4 is a cross-section of still another form of my improved rail-

25 joint.

My improved rail-joint is constructed on the principle of the invention shown in the United States Patent No. 532,431, granted on January 8, 1895, to G. A. Hoffmann and 30 M. Friedlander, and is a further development of said patented invention, which has been assigned to the firm of Ausfuehrungen fuer Eisenbahn Oberbau, Abth. Stossfangschiene, Siegm. Eppenstein, of which I am a member.

35 In this patent there is shown an auxiliary rail which is arranged alongside the main rails, at the joint thereof, and has its head curved or beveled downwardly at the ends and also sloped transversely. In my present

40 invention the same features may be employed together with a filling-piece or fish-plate which is located between the main rails and the auxiliary rail, as described in said patent. It has been found desirable in some cases to 45 give an increased strength to the auxiliary rail. The most obvious course would be to simply increase the thickness of the web of said auxiliary rail. This, however, is open to the objection that either the auxiliary rail

or the filling-piece or fish-plate will become 50 unsymmetrical in this case. To overcome the difficulty and to secure a proper engagement of the several parts of the joint, as will be set forth in detail hereinafter, I do not increase the thickness of the web of the auxiliary rail at those points at which said web is in contact with the filling-piece, but I do give an increased thickness to the web of the auxiliary rail between those points.

As illustrated by Fig. 1, A is one of the 60 main rails, B is the auxiliary rail, having the transversely-sloping top surface B' and having its base B² recessed upon one side so as to accommodate (with play) the base of the main rail, and C is the double-headed filling- 65 piece. This filling-piece engages the heads and bases of both rails and also the webs of the rails adjacent to the heads and bases. The whole structure is held together by bolt D, working in connection with a fish-plate E, 70 washer F, and nut G. This bolt may have a relatively tight fit in the webs of the two rails; but the bolt-holes C' in the filling-piece are lengthened, so as to allow of some vertical play. The web of the auxiliary rail has two 75 portions B³, which are symmetrical relatively to the center of the rail-head. Between these two web portions B³ is located an outwardly-bulged unsymmetrical web portion B⁴, and in this web portion the bolt-holes are provided. 80

In Fig. 2 the construction differs from that just described merely by the fact that the enlargement B⁵ of the auxiliary-rail web is located upon the inner surface of said web. It will be observed that in this case the heads of 85 the filling-piece C are not in engagement with the enlarged portion B⁵, so that there is some play allowed for a slight up or down movement of the filling-piece.

The construction shown in Fig. 4 shows a 90 combination of the features represented in Figs. 1 and 2—that is, the auxiliary-rail web is bulged both inwardly and outwardly between the two portions B³. Fig. 4 also shows an additional feature, which may be valuable—namely, the provision of a groove B⁶ upon the outer surface of the web, which groove is adapted to receive the angular head

D' of the bolt D, so that said bolt will be held positively against turning, thus reducing the liability of the nuts G becoming loose.

I desire to call particular attention to the fact that the filling-piece C is symmetrical, so that the web of said filling-piece is vertical below the abutting side surfaces of the rail-heads. The web of the main rail is of course symmetrical relatively to the head thereof, and the web portions B³ of the auxiliary rail are also symmetrical relatively to the head of the auxiliary rail, the full width of said head being equal to the width of the main-rail head. I thus obtain a very strong construction without destroying the symmetrical arrangement of the parts. With an unsymmetrical arrangement there would arise strains tending to turn or tip either the main rails or the auxiliary rail sidewise. An important practical advantage of the constructions shown is that the auxiliary rail may be produced in a rolling-mill even when the groove B⁶ is employed, it being understood that this groove would extend uniformly from end to end of the auxiliary rail.

I claim as my invention and desire to secure by Letters Patent—

1. A rail-joint comprising in combination a main rail, an auxiliary rail, the head of which abuts against the main rail, a double-headed filling-piece arranged between the webs of the said rails, the web of the auxiliary rail being of relatively small thickness at the points where it is engaged by the said filling-piece, and of increased thickness between said points, and means for connecting the auxiliary rail with the main rail.

2. A rail-joint comprising in combination a main rail, an auxiliary rail, the head of which

abuts against that of the main rail, said auxiliary rail having a web with relatively thin portions adjacent to its head and base and with a central portion of greater thickness, a filling-piece located between the webs of the main rail and the auxiliary rail and provided with heads which engage the web of the auxiliary rail at the thin portions thereof, and bolts passing through the webs of the rails and loosely through the web of the filling-piece.

3. A rail-joint comprising a main rail, an auxiliary rail abutting against it and provided with an outwardly-thickened web portion provided with a longitudinal groove, a filling-piece located between the webs of the main rail and the auxiliary rail, and bolts connecting the said rails and having angular heads seated in the groove of the auxiliary rail.

4. A rail-joint comprising a symmetrical main rail, an auxiliary rail having a head of the same width as that of the main rail, and also having a web located symmetrically to the head adjacent to the said head and to the base, and of relatively small thickness at those points, the intermediate or central portion of the web being of increased thickness, a double-headed filling-piece, the heads of which engage the web of the main rail and also engage the web of the auxiliary rail at the thin portions thereof, and connecting-bolts extending through the webs of the rails and loosely through the web of the filling-piece.

MAX BARSCHALL.
